UNITED STATES PATENT OFFICE.

RICHARD S. BATES, OF STERLING, COLORADO.

ROAD GRADER.

1,405,256.

Specification of Letters Patent. Patented Jan. 31, 1922.

Application filed November 2, 1920. Serial No. 421,337.

To all whom it may concern:

Be it known that I, RICHARD S. BATES, a citizen of the United States, residing at Sterling, in the county of Logan and State 5 of Colorado, have invented new and useful Improvements in Road Graders, of which the following is a specification.

My present invention has for its object to provide a road grader characterized by the 10 capacity to pulverize the dirt raised by a grader blade, and to throw such dirt to the road bed.

To the attainment of the foregoing the invention consists in the improvement as 15 hereinafter described and definitely claimed.

In the accompanying drawings, hereby made a part hereof:—

Figure 1 is a side elevation of the grader constituting the best practical embodiment 20 of my invention of which I am cognizant.

Figure 2 is a plan view of the same.

Figures 3, 4 and 5 are enlarged detail views of one of the knives comprised in the grader; Figure 5 being taken in the plane indicated by the line 5—5 of Figure 3.

Similar numerals of reference designate corresponding parts in all of the views of the drawings.

In addition to an appropriate frame 1, 30 supported by ground wheels 2, my novel grader comprises a grader blade 3 and rotary cutters and throwers 4; the said rotary cutters and throwers being arranged in a pair and in the relation illustrated in Figures 1 and 2 to the grading blade 3. The grading blade 3 is shown as connected through a rod 5 with one arm of a lever 6, fulcrumed at 7 on the frame 1, and having its other arm connected to a rack bar 8 that 40 is intermeshed with a spur gear 9 fixed with respect to a hand wheel 10 through the medium of which the grading blade 3 may be adjusted and adjustably fixed by an attendant standing upon the platform 11. This, 45 however, is not of the essence of my invention, and I would therefore have it understood that the grading blade 3 may be connected with the frame 1 in any appropriate manner that will permit of the said blade 3 being adjusted vertically.

Carried on the frame 1 is a motor 12, preferably of internal combustion type. The drive shaft 13 of the said motor is connected with the upright shafts 14 of the rotary 55 cutters and throwers so as to rotate said cutters and throwers in opposite directions; the

specific driving connection illustrated including a miter gear 15 on the shaft 13, an auxiliary shaft 16, a miter gear 17 fixed on said shaft 16 and intermeshed with the miter gear 15, a second miter gear 18 fixed on the shaft 16, a miter 19 fixed on one shaft 14 and intermeshed with the miter gear 18, and intermeshed spur gears 20 fixed on the two shafts 14.

In addition to a shaft 14 each rotary cutter and thrower includes a plurality of knives 21, specifically shown in Figures 3, 4 and 5; the knives of the two cutters and throwers being arranged in the relation clearly illustrated in Figures 1 and 2, it being remembered in this connection that the cutters and throwers are synchronously rotated in opposite direction.

Each of the said knives 21 is adapted at 22 to be fixed to its respective upright shaft, and each is provided with a back wall 23, disposed at right angles to its body 24, and has the edge of its said body 24 sharpened, as indicated by 25, sharpened edge extending 80 from the outer end of the wall 23 to the inner thickened or enlarged portion 26 of the knife.

In the practical use of my novel grader, it will be understood that in operation the rotary cutters and throwers will serve to 85 sufficiently pulverize and deliver dirt to the road bed as the dirt is plowed up by the blade 3. In this connection it will be noted that the outer end of the blade 3 is positioned at 90 a point between the radii of the knives of the two cutters and throwers, at which point the dirt from the blade 3 is delivered to the cutters and throwers. It will also be noticed that the knives are heavy and broad and are somewhat curved in the direction of their 95 lengths so as to enable them to catch the dirt as they pass through the same and to carry the dirt with them and deliver the same to the road bed. This result is attained in large measure by the provision of the walls 100 23 on the knife bodies 24. It will also be understood that the knives of the two cutters and throwers move outwardly from between said cutters and throwers; that the knives do not interfere in any measure with each 105 other; and that the knives of the two cutters and throwers operate to carry slices of dirt from the blade 3 between the two cutters and throwers, whereupon the latter operate to throw the dirt outwardly to the road bed 110 and contribute to the making of a grade.

It will be apparent from the foregoing

that my novel means for pulverizing and throwing the dirt is simple, compact and strong, and that it is highly efficient for the purpose ascribed to it.

Having described my invention, what I claim and desire to secure by Letters-Patent, is:—

1. In a road grader, the combination with a grader blade, of a pair of rotary cutters and throwers to pulverize and deliver dirt raised by the blade; each of the said cutters and throwers having knives with angularly disposed backs, and the knives of the two cutters and throwers being arranged to lap and fast each other in parallel horizontal planes.

2. In a road grader, the combination with a grader blade, of a pair of rotary cutters and throwers to pulverize and deliver dirt

raised by the blade; each of the said cutters and throwers having knives with angularly disposed backs, and the knives of the two cutters and throwers being arranged to lap and fast each other in parallel horizontal planes, and the outer end of the grader blade being disposed at a point adjacent to the radii of the two cutters and throwers.

3. In a road grader, the combination of a wheel supported frame, a vertically adjustable grader blade carried by said frame, manual means to adjust said blade, a motor on the frame, rotary cutters and throwers with the blade and each having knives arranged to lap and fast each other in parallel planes, and each having backs on their knives, and a driving connection intermediate of the motor and said cutters and throwers.

RICHARD S. BATES.
